Primary Examiner — Mark A Goodwin(74) *Attorney, Agent, or Firm* — Novick, Kim & Lee PLLC; Jae Youn Kim(57) **CLAIM**

We claim the ornamental design for a part for excavator bucket, as shown and described.

DESCRIPTION

FIG. 1 is a top, front, right side perspective view of a part for excavator bucket, showing our new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, rear, right side perspective view thereof.

The broken lines in the drawings show portions of the part for excavator bucket that forms no part of the claimed design.

1 Claim, 6 Drawing Sheets(56)
